UNITED STATES PATENT OFFICE.

AMOS M. LEE AND ELMER J. HAGREEN, OF ROCHESTER, NEW YORK.

DESK PAD.

Application filed September 20, 1921. Serial No. 502,066.

To all whom it may concern:

Be it known that we, AMOS M. LEE and ELMER J. HAGREEN, citizens of the United States, residing at Rochester, in the county 5 of Monroe and State of New York, have invented certain new and useful Improvements in Desk Pads, of which the following is a specification.

The object of this invention is to provide 10 a new and improved form of desk pad.

This and other objects will be fully illustrated in the drawings, described in the specification, and pointed out in the claims at the end thereof.

15 In the drawings:

Figure 1 is a top plan view of the pad.

Figure 2 is a side elevation of the pad.

Figure 3 is a vertical longitudinal section through the pad.

20 Figure 4 is a side elevation of a modified form of the pad.

In the several figures of the drawing, like reference numerals indicate like parts.

In the drawing, reference numeral 1 indicates the base of the pad which is covered 25 on the bottom with a suitable substance that will act as a cushion, and hold the pad against sliding, a sheet of corrugated rubber being preferably used for this purpose.

30 Extending up from the base are the sides 3 and 4 as well as the ends 5 and 6. The end 6 forms part of a semi-cylindrical receptacle 7 as shown at the left of Figure 3. The inclined top is provided which slopes 35 from the upper end of the end 6 to the upper end of the end 5.

The end 5, inclined top 8, and semi-cylindrical receptacle 7, of which the end 6 forms 40 part thereof, is preferably formed of a single sheet of metal bent to the desired form. The sides 3 and 4 are attached to the inclined top 8 and are bent down therefrom and are suitably fastened to the base 1. The free space between the top 8 and the base 1 may 45 be filled with any desirable substance to weight the pad and hold it in place on the desk.

On top of the semi-cylindrical receptacle 7 is hinged the semi-cylindrical cover plate 50 9 which completes the cylindrical receptacle into which a paper roll 25 is adapted to be placed. The cover plate 9 is provided with a flange 10 on the free end thereof, which flange rests on the top 8 when the cover is 55 in its closed position. The cylindrical receptacle is closed on the ends by the circular

end plates 11 and 12 forming part of the sides 3 and 4.

As heretofore pointed out, the cylindrical receptacle is adapted to hold a roll of paper 60 suitable for writing, which roll is held loosely in place therein by reason of its own weight. For this purpose the cover may be raised and a roll of paper 25 may be placed therein and the loose end thereof may be 65 drawn out on the top 8. The cover 9 is then swung into place as shown in Figure 3 and is held in that position by the spring flanges 13 and 14 which grip the sides 3 and 4 and hold it firmly in place with a slight 70 interval between the flange 10 and the top 8 through which the paper can pass as it is drawn out from the receptacle.

On the lower end of the top 8 is provided 75 a sliding plate 15 which extends across the paper and has the flanges 16 and 17 turned down on the ends thereof. The bottom of these flanges is turned in as indicated at 18 and 19 to engage into the longitudinal slots 20 and 21 in the sides 3 and 4 respectively. 80 By these flanges and their engagement with the sides 3 and 4, the plate 15 is held in a suitable position above the top 8 with the end of the paper web placed between the plate and the top.

85 The slots 20 and 21 extend horizontally in the sides 3 and 4 and guide the plate 15 in a horizontal movement. The plate 15 is normally held in the position shown in Figure 2 by the springs 22 and 22^A which are 90 connected to lugs formed on the sides 3 and 4 at the left, and to the flanges 17 and 18 at the right. By the tension of these springs the plate 15 is normally held in position as shown in Figure 2 and in this position the 95 forward edge of the plate 15 bears sufficiently against the top 8 to hold a paper web in position thereon.

The end of the top plate 8 is cut away at 100 the right as indicated in dotted lines at 23 so as to expose the under side of the paper to the finger of the operator. This enables the operator to place his finger on the under side of the end of the paper web and his thumb on top of the plate 15 so that he can 105 draw the paper and the plate together to the position illustrated in Figure 3. On the release of the plate 15 and the end of the paper web the plate returns to its normal position shown in Figures 1 and 2, leaving 110 the end of the paper pulled out with the plate 15 exposed. The exposed end of paper

can then be taken hold of and drawn out as far as may be desired and then torn off against the edge of the plate 15, leaving a fresh sheet of paper on the inclined top 8 to receive another record that may be placed thereon.

In Figure 4 the receptacle for the paper roll is shown provided at the top with a spring pressed paper clip 26 with which 10 may be clamped any memoranda torn off the paper web which it is desired to preserve.

We claim:

1. In a desk pad, the combination of a receptacle, a writing table formed at one end of said receptacle, said receptacle having a pocket formed therein to receive a roll of paper from which a continuous web of paper may be drawn over said writing table, horizontally movable clamping means at the free end of said writing table, said clamping means being adapted to move away from said table, said clamping means being adapted to hold the free end of the paper web 20 against said writing table and permit the end of the paper web to move away from said writing table with said clamping means on the operation of said clamping means.

2. In a desk pad, the combination of a receptacle, a writing table formed at one end of said receptacle, said receptacle having a pocket formed therein to receive a roll of paper from which a continuous web of paper may be drawn over said writing table, a 30 cover for said receptacle, a flange formed on said cover over hanging said writing table to guide the beginning of the paper web from the paper roll onto said writing table, a clamping bar at the free end of said writing

table, means for operating said clamping bar to hold the free end of the paper web against the end of said writing table, said clamping bar being adapted to be moved simultaneously with the end of paper web to release the end of the paper web and feed it 40 a short distance from the writing table, the paper web being left in its advanced position on the release of said clamping bar to again clamp the end of the paper web onto the writing table.

3. In a desk pad, the combination of a receptacle, a writing table formed at one end of said receptacle, said receptacle having a pocket formed therein to receive a roll of paper from which a continuous web of paper may be drawn over said writing table, a cover for said receptacle, a flange formed on said cover over hanging said writing table to guide the beginning of the paper web from the paper roll onto said writing table, a clamping bar at the free end of said writing table, means for operating said clamping bar to hold the free end of the paper web against the end of said writing table, said clamping bar being adapted to be moved simultaneously with the end of paper web to release the end of the paper web and feed it 50 a short distance from the writing table, the paper web being left in its advanced position on the release of said clamping bar to again clamp the end of the paper web onto the writing table.

In testimony whereof we affix our signatures.

AMOS M. LEE.
ELMER J. HAGREEN.
